UNITED STATES PATENT OFFICE.

WILHELM B. BRONANDER, OF MONTCLAIR, NEW JERSEY, ASSIGNOR TO INTERNATIONAL CIGAR MACHINERY COMPANY, A CORPORATION OF NEW JERSEY.

CIGAR-BUNCH-CHARGE FORMER.

Application filed March 15, 1924. Serial No. 699,488.

To all whom it may concern:

Be it known that I, WILHELM B. BRONANDER, a citizen of the United States, residing at Montclair, county of Essex, and 5 State of New Jersey, have invented a new and useful Improvement in Cigar-Bunch-Charge Formers, of which the following is a specification.

This invention relates to a cigar bunch 10 charge former, particularly, but not necessarily, adapted for use in connection with a bunch rolling mechanism in which charges of filler are fed along a table to an element of the rolling mechanism and then lowered 15 with said element into position to be rolled into a bunch.

The main object of the invention is the 20 production of a machine for converting substantially flat charges of filler into arcuate form before the bunch rolling begins. Another object is the production of a machine of this type in which the leaves of the charge are fanned out somewhat during the arcuate 25 formation of the charge. It has been discovered that by so forming the charges just prior to rolling, bunches simulating the well known "Spanish" bunches can be automatically produced, thus eliminating the necessity heretofore existing for manually spreading 30 or fanning out the leaves on the rolling table, preparatory to rolling. With these and other objects not specifically mentioned in view, the invention consists in certain 35 constructions and combinations which will be hereinafter fully described and then specifically set forth in the claims hereunto appended.

In the accompanying drawings, which 40 form a part of this specification and in which like characters of reference indicate the same or like parts, Fig. 1 is a front elevation of a device constructed in accordance with the invention; and Figs. 2 and 3 are detail fragmentary views illustrating certain 45 parts of the device shown in Fig. 1 but in different positions.

In carrying the invention into effect, there is provided a suitable bunch rolling mechanism including an element receiving a charge 50 of filler in substantially flat form; and to coat therewith, there is further provided means acting on the charge to convert it into arcuate form before bunch rolling begins, in order to prepare the charge to be rolled up from one of its edges as in a "Spanish" 55

bunch. In the best constructions, there is further provided devices whereby the leaves of the charge of filler are spread or fanned out during arcuate formation. The mechanisms, means and devices above referred to 60 may be widely varied in construction within the scope of the claims, for the particular structure selected to illustrate the invention is but one of many possible concrete embodiments of the same. The invention, 65 therefore, is not to be restricted to the precise details of the structure shown and described.

Referring to the drawings, 4 indicates a chianti belt forming a part of a bunch rolling mechanism; 5 indicates the loop forming element of said mechanism; 6 indicates the belt tensioning device; and 7 indicates the bunch rolling table. Above the tensioning device 6, a feed table 8 is located along 70 which charges of filler are fed by means of a plunger 9 having a reciprocating movement. The structure so far described is old and well known in the art and a detailed description of the same being unnecessary to a full understanding of the present invention, it is omitted in the interest of brevity and clearness.

The chianti belt 4 lies over a platen 10, 85 also of well known construction, the purpose of the platen being to elevate the chianti belt to the level of the feed table 8 in order that it may receive a charge of filler tobacco in substantially flat form, and lower it into position for rolling within a binder to form 90 a bunch. The platen 10 has a reciprocating movement and is cam actuated. With this end in view, it is mounted upon the upper end of a rod 11 sliding in bearings 12-13 formed on a bracket 14 mounted on a bar 15, 95 the latter being suitably supported from the main frame of the cigar machine in connection with which the device is used. The rod 11 is prevented from turning by means of two slides 16 clamped thereon and engaging a suitable slideway 17 formed on the bracket 14 before referred to. The lower end of the rod 11 is pivoted to the upper end of a connecting rod 18, the lower end of this connecting rod being pivoted to a cam lever 19 fulcrumed on a bar 20, extending across the machine. The cam lever 19 carries a cam bowl 21 tracking in a suitable groove in the cam 22 fast on the cam shaft 23 which is one of the main cam shafts of the cigar 100 105 110

machine. It will be readily understood that the groove of the cam 22 is formed to produce the reciprocating movement of the platen 10 at the proper time.

5 Means are provided which act on the charge to convert it into arcuate form before bunch rolling begins. As shown, this means includes a follower 24 which is angular in cross-section and shaped to engage a 10 substantially flat charge marked C, Fig. 2, a little to one side of the middle thereof, for a purpose which will presently appear. The follower 24 has a reciprocating movement which is cam actuated. With this end in 15 view, it is mounted upon the upper end of a rod 25, slidably in suitable bearings 26 and 27, formed on the bracket 28, fast to the bar 15 before referred to. The rod 25 is prevented from turning by a pair of slides 29 20 clamped thereon and engaging a slideway 30 formed in the bracket 28. The lower end of the rod 25 is pivoted to the upper end of a connecting rod 31, and the lower end of this connecting rod is pivoted to the free 25 end of a cam lever 32, fulcrumed on the bar 20 before referred to. The cam lever 32 carries a cam bowl 33 tracking in a suitable groove in the cam 34 fast on the cam shaft 23 before referred to. It will be readily 30 understood that the groove of the cam 34 controls the movement of the follower 24 in proper timed relation with the movement of the platen 10 supporting the charge C.

35 Fig. 2 illustrates the platen 10 and the follower 24 in the position they occupy when a charge has just been moved from the feed table 8 on to the chianti belt 4 overlying the platen. The platen and follower then move downward, the follower moving at a 40 greater rate of speed than the platen in order to overtake the charge being lowered before the platen reaches its lowermost position. As the platen approaches the end of its downward movement, the loop is formed 45 in the chianti belt, and the lower edge of the follower 24 engages the charge C to one side of its mid-section. A little further downward movement of its parts results in spreading or fanning out the leaves of the 50 charge C and in simultaneously converting said charge from its initial substantially flat form to the arcuate form as clearly shown in Fig. 3. As soon as this is accomplished, the follower 24 is given a rapid upward 55 movement so that the loop forming roller 5 can come into action and roll the charge. When the charge is disposed, as shown in Fig. 3, the rolling begins at one edge of the charge, as in a "Spanish" bunch, so that 60 when the bunch is completed the several leaves of the charge are rolled up in spiral form within the binder. In this way a bunch is produced which simulates the well known "Spanish" bunch; and this eliminates 65 the necessity heretofore existing for manu-

ally spreading or fanning out the leaves of the charge on the rolling table when a "Spanish" bunch is to be made.

What is claimed is:

1. In a cigar machine, the combination 70 with bunch-rolling mechanism including an element receiving a charge of filler in substantially flat form, of means acting on the charge at one side of its center to fan out and convert it into arcuate form before bunch rolling begins, said element being in the form of a chianti belt, and said means acting on the charge during the formation of the belt loop.

2. In a cigar machine, the combination 80 with bunch-rolling mechanism including an element receiving a charge of filler in substantially flat form, of means acting on the charge to convert it into arcuate form before bunch rolling begins, said means engaging the charge at one side of its centre to fan out the leaves thereof during arcuate formation.

3. In a cigar machine, the combination 90 with bunch rolling mechanism including an element receiving a charge of filler in substantially flat form, of means acting on the charge at one side of its center to fan out and convert it into arcuate form before bunch rolling begins, said means including 95 a movable platen for lowering said element and a charge thereon into position for arcuate formation of the latter.

4. In a cigar machine, the combination 100 with bunch rolling mechanism including an element receiving a charge of filler in substantially flat form, of means acting on the charge at one side of its center to fan out and convert it into arcuate form before bunch rolling begins, said means including 105 a cam-actuated reciprocating platen for lowering said element and a charge thereon into position for arcuate formation of the latter.

5. In a cigar machine, the combination 110 with bunch rolling mechanism including an element receiving a charge of filler in substantially flat form, of means acting on the charge at one side of its center to fan out and convert it into arcuate form before 115 bunch rolling begins, said means including a movable platen for lowering said element and a charge thereon into position for arcuate formation of the latter, and a follower producing the arcuate formation of 120 the charge near the end of the platen movement.

6. In a cigar machine, the combination 125 with bunch rolling mechanism including an element receiving a charge of filler in substantially flat form, of means acting on the charge at one side of its center to fan out and convert it into arcuate form before bunch rolling begins, said means including 130 a movable platen for lowering said element

and a charge thereon into position for arcuate formation of the latter, and a cam-actuated follower producing the arcuate formation of the charge near the end of the 5 platen movement.

7. In a cigar machine, the combination with bunch rolling mechanism including an element receiving a charge of filler in substantially flat form, of means acting on the 10 charge at one side of its center to fan out and convert it into arcuate form before bunch rolling begins, said means including a cam-actuated reciprocating platen for lowering said element and a charge thereon 15 into position for arcuate formation of the latter, and a cam-actuated reciprocating follower producing the arcuate formation of the charge near the end of the platen movement.

8. In a cigar machine, the combination 20 with bunch rolling mechanism including an element receiving a charge of filler in substantially flat form, of means acting on the charge at one side of its center to fan out and convert it into arcuate form before 25 bunch rolling begins, said element being in the form of a chianti belt, and said means including a cam-actuated reciprocating platen for lowering said belt and a charge 30 thereon into position for arcuate formation of the latter, and a cam-actuated reciprocating follower producing the arcuate formation of the charge during the formation of the belt loop.

In testimony whereof, I have signed my name to this specification.

WILHELM B. BRONANDER.
